APPARATUS FOR EXPRESSING LIQUIDS

Stanley Hiller, Berkeley, Calif., assignor to
 Stanley Hiller, Incorporated, San Francisco,
 Calif., a corporation of California

Application November 22, 1929, Serial No. 409,125

12 Claims. (Cl. 100—48)

The present invention relates to high pressure presses, and more particularly to continuous high pressure screw presses for expressing fats and oils from diverse materials such as fish, fish-
 5 waste, packing offal, garbage, cracklings from rendering processes, copra, cotton seed, and like oil bearing substances.

A primary object of the invention is to provide an efficient high pressure press of novel construction adapting it for most efficient operation as
 10 well as being relatively inexpensive to manufacture.

A further object of the invention is the provision of a novel press structure embodying parts
 15 which are arranged for ready removal thus adapting the structure for ready accessibility for cleaning or for replacement of parts.

A still further object of the invention is the provision of novel control mechanism for discharge cones of high pressure presses whereby rapid and easy adjustments of the discharge cone may be made to vary the thickness of the cake and consequently the pressure developed on
 20 the materials from which oils are being ex-
 25 pressed.

A still further object of the invention is the provision of a novel screen structure adapted for detachable association with a press barrel in proximity to the revolving screw therein and the method of making such screens.

A still further object of the invention is the provision of novel tempering and charging apparatus whereby the material is heated, agitated and force fed into the press with which the tempering and charging apparatus is operatively connected.

Further objects of the invention are the provision of novel driving arrangements and bearing structures, the provision of various improved combinations and sub-combinations of mechanisms, and the attainment of such other objects as will more fully appear in the following detailed description of the preferred embodiments of the invention.

45 Referring to the accompanying drawings forming a part of the present disclosure and in which is illustrated preferred physical embodiments of the present invention:

Figure 1 is a part side elevation and part axial vertical sectional view of a press structure and tempering apparatus constructed in accordance with a preferred embodiment of the invention.

Figure 2 is a view partly in top plan and partly in horizontal section as seen on line 2—2 of Figure 4.

Figure 3 is a transverse vertical sectional view substantially on a plane represented by line 3—3 of Figure 1.

Figure 4 is an end elevational view as seen in the direction represented by the arrow 4 in Figure 1.

Figure 5 is a transverse sectional view of one of the press barrel members in a slightly modified form showing the application therewith of a preferred form of screen structure embodied in my invention.

Figure 6 is an outer plan view of a portion of the screen structure illustrated in Figure 5.

Figure 7 is a view similar to Figure 5 illustrating a further form of screen structure.

Figure 8 is an enlarged transverse section of a portion of the screen structure illustrated in Figure 7.

Figure 9 is a broken plan view showing the successive laminae forming the screen structure shown in Figures 7 and 8.

Figure 10 is a transverse section thru a further form of screen structure and Figure 11 is a similar view of a still further form of screen structure.

Referring to the accompanying drawings by reference characters in which like characters designate like parts, 11 designates a pair of end castings providing supports for the structure later described and upon which is supported the opposite ends of an oil collecting pan member 12 more fully described hereinafter. Supported on and detachably secured to member 12 intermediate the ends thereof as indicated at 13 is the flanged foot portion 14 of a hopper casting 15 and detachably secured to one end of member 12 in spaced relation to casting 15 as indicated at 16 is the foot portion 17 of a discharge end casting 18. Detachably connected with the end of member 12 opposite the end to which casting 18 is secured as indicated at 19 are integral brackets 21 of a gear housing 22 which housing is provided with a circular flange 23 defining a circular opening for receiving a cylindrical extension 24 of casting 15.

The flange 23 of gear housing 22 is detachably secured to a flange 25 of casting 15 by means of bolts 26. Gear housing 22 is open ended and provided with a marginal flange 28 at the outwardly facing end thereof to which is detachably secured by means of bolts 29 a flange 31 of a cover plate 32.

The cover plate 32 is provided with a cylindrical extension 33 having integrally formed bracing ribs 34. Cylindrical extension 33 is provided with a shaft bearing bushing 35 for one end of a shaft 36. Shaft 36 extends the full length of the ma-

55

chine and the opposite end thereof has mounted thereon a cone member 37 which is keyed to shaft 36 for longitudinal adjustment relative thereto by a key 38 and cone member 37 is rotatably journaled in a bearing bushing 39 in the hub portion 41 of a spider casting 42, the casting 42 comprising in addition to hub 41 angularly disposed arms 43 integral at corresponding ends with hub 41 and integral at their opposite ends with a circular ring member 44 which ring member engages casting 18 within an outwardly directed flange 45 thereof and is detachably secured to casting 18. The shaft 36, it will be seen, is rotatably journaled within bushings 35 and 39 adjacent opposite ends thereof. The shaft 36 has additional bearing within a bushing 47 mounted within the bore of a thrust bearing retaining ring 48 which is provided with a flange 49 detachably secured to cylindrical extension 24 of casting 15 by means of bolts 51. The shaft 36 is of various diameters and includes a substantially long section 52 of uniform diameter intermediate bushing 47 and cone 37. Suitably keyed to shaft 36 for rotation therewith is a bearing member 53 which is mounted on shaft 36 from the end thereof adjacent the discharge end of the press, one end of which engages a shoulder 54 of shaft 36 between portion 52 and an enlarged portion 55 which is rotatably journaled in bushings 35 and 47. Bearing member 53 is retained on shaft 36 by means of a collar 56 engaging the opposite end of member 53 which in turn is engaged by the adjacent one of a plurality of screw sections 57, 58, 59, 61, 62 and 63 of successively increasing diameter and which are maintained in spaced relation by conical spacing collars 64, 65, 66, 67 and 68 respectively. The screw sections and spacing collars are suitably keyed to shaft 36 for longitudinal mounting thereon and for rotation with the shaft. The outer screw section 63 at the outer end thereof is undercut providing a recess 71 for the reception of the reduced cylindrical extension 72 of a retaining nut 73 threadedly engaged with shaft 36 as is indicated. Bearing member 53 is provided with a circular seat 75 for the inner race 76 of a thrust ball bearing assembly 77 the outer race 78 of which is seated in engagement with cylindrical extension 24 and ring member 48. A suitable lubricating connection 79 extends through housing 22 and casting 15 for introducing lubricant to the bearing 77. Casting 15 is provided with a lubricating packing 81 for lubricating the bearing surface of member 53.

It will be seen upon inspection of Fig. 1 that the bearing member 53 is provided with two longitudinally spaced bearing surfaces 53' and 53'' in rotatable engagement with the walls of separated bearing openings in casting 15 and that packing 81 retains lubricant in the thrust bearing cavity and prevents leakage thereof into the space 50 between surfaces 53' and 53''.

The space 50 is enclosed above the center line of shaft 36 but is entirely open below the center line of the shaft whereby any material working its way out of the feed hopper later described into space 50 drops out of the casting and thus cannot possibly get into the thrust bearing cavity.

Furthermore any lubricant leaking out of the thrust bearing cavity drops out of space 50 and thus cannot possibly get into the feed hopper.

Removably disposed between castings 15 and 18 is a press cage 82 comprising a pair of mating sections 83 with the cooperating faces thereof disposed in a vertical longitudinal plane as clearly indicated in Figure 3. Each of the sections 83

has end flanges 84 for detachable connection with the respective faces of castings 15 and 18 by means of bolts 85 and 86, the bolts 85 detachably securing the upper and lower elongated extensions of flanges 84 in position and the bolts 86 securing said flanges to said castings at intermediate portions thereof. Each section 83 further includes integral with flanges 84 a pair of vertically disposed relatively heavy bars 88 which are recessed adjacent their inner edges as indicated at 89 for a purpose later described and integral with bars 88 and longitudinally spaced between the opposite end flanges 84, are ribs 91 which with bars 88 of opposite sections 83 define a cylindrical bore 92 for a purpose later described. Each section 83 further includes integral longitudinally extending ribs 93 which as indicated in Figure 3 are disposed radially of shaft 36 and are slightly spaced at the bases thereof from the inner surface of ribs 91 as indicated at 94 for a purpose later described. Bars 88 in the assembled position of sections 83 are detachably secured together by upper and lower longitudinal series of transversely disposed bolts 95 which project through bars 88 and bosses 96 integral with the opposing faces of bars 88.

It will be seen from the above that a press cage is provided for encircling relation with shaft 36 which is readily removable to facilitate ready cleaning as well as for ready access to parts within the cage about to be described.

The bore 92 within cage 82 receives shaft 36 centrally thereof and cage 82 has removably secured within the bore 92 thereof a screen structure 98 which provides a press barrel between which the spiral screw flights of the screw sections the material is subjected to pressure for extracting the fats and oils therefrom, the screw flights substantially contacting the inner cylindrical wall of screen 98 as indicated in Figures 2 and 3.

Removably secured within recesses 89 of bars 88 are knife bars 99 which as indicated in Figure 1 are preferably secured to the bars 88 of one of the sections 83 by screws 101. The knife bars 99 are provided with check projections 103 which project inwardly and have their inner edges correspondingly inclined to and slightly spaced from the outer surfaces of the conical spacing collars 64 to 68 inclusive. The screen structure 98 is preferably in semi-cylindrical sections, each section disposed within the bore 92 of each cage section 83 and with the opposite edges of the screen sections engaging opposite faces of knife bars 99 in the assembled relation of the parts as illustrated in Figure 3.

The screen structure 98 as illustrated in Figures 2 and 3 comprises a plurality of longitudinal sections supported within each cage section 83 as indicated at 104 in Figure 2 and each section is preferably composed of longitudinal extending slightly spaced bars 105 for providing relatively thin openings for the egress of oils and fats expressed from the material within the cage. The screen structure is a very important feature in presses of this general character, various forms of which are disclosed in the drawings and are about to be described.

A preferred embodiment of screen structure and which has been found best adapted to the character of work accomplished by presses of this character is illustrated in Figures 5 and 6 in which the screen structure is supported within slightly modified forms of press cage sections 83' and in which the screen sections designated at 111 are of semi-cylindrical formation with the adjacent

edges thereof in engagement with the opposite sides of knife bars 99. Each screen section 111 is constructed of a plurality of longitudinally extending bars 112 which as clearly indicated in Figure 6 are welded together at longitudinally spaced points as indicated in 113 thus providing an integral member having a plurality of series of longitudinal slits 114 separated by the relatively narrow welded portions 113. The welded portions 113 are essential only for connecting the bars 112 for preventing separation thereof and in welding the bars 112 together the points 113 of welding are so spaced longitudinally of the screen member that in assembled relation they will rest opposite the transverse ribs 91 of the press cage 82 whereby the welding of bars 112 in the manner disclosed will in no way detract from the efficiency of the screen member. The bars 112 as more clearly indicated in Figure 5 are provided with inner and outer plane faces with the opposite sides thereof converging outwardly from the inner to the outer faces as indicated at 116 thus providing outwardly diverging slits 117 between the bars 112, the construction as disclosed providing relatively narrow slits opening into the inner surface of screen members 111 with the slits diverging outwardly at a relatively large angle whereby a screen structure is provided having relatively narrow slits on the inner or active surface thereof for the passage of oils and fats therethrough. By the provision of the outwardly diverging slits the oils or fats upon entering same are permitted to expand and consequently pass through the screen members 111 with little liability of clogging the slits therein.

Although I have illustrated the above screen as made up of bars having a cross section of a truncated cone, it will be clear that bars of various other cross sections could be used, the only essential being that the longitudinal slots therebetween flare outwardly. For example, the bars could be rectangular in cross section and when assembled about a central axis the slots will be flaring.

The screen structure as above described may be produced in various other ways than the assembly and welding of separate bars, since for example a screen could be cast with a plurality of longitudinal slots flaring outwardly, or said slots could be cut into a suitably shaped metal shell.

It will be seen from the above that in accordance with this embodiment of the invention a screen structure is provided which is of sufficient rigidity to withstand the relatively high pressures therein and at the same time embodies relatively narrow oil passages.

A further form of screen structure is illustrated in Figures 7, 8 and 9 and comprises a pair of semi-cylindrical sections as in the previous embodiments of the invention each of which sections comprises an inner perforated plate 119 and an outer slightly thicker perforated plate 121, the plates 119 and 121 being spaced apart and enclosing a layer of porous material such as hair cloth or similar material. It has been found that camels hair cloth 122 of a thickness approximately equal to the combined thicknesses of plates 119 is especially effective. As illustrated in Figure 7 the layer of camels hair cloth 122 extends from one knife bar 99 to the other but the plates 119 and 121 have their edges turned outwardly into abutting relation and engaged within the bases of recesses 123 in press cage sections 83' in which recesses 123 knife bars 99 are secured in engagement with the outwardly turned edges of

plates 119 and 121. In accordance with this embodiment of the invention as well as that illustrated in Figure 5 a pair of knife bars 99 are carried by each section 83' for side contacting engagement in the assembled position of cage sections 83'.

A still further form of screen structure is illustrated in Figure 10 and which comprises inner and outer perforated plates 125 and 126 similar to the plates 119 and 121 but in this form of screen structure the plates 125 and 126 enclose a layer 127 of fine mesh woven wire screen in place of the camels hair cloth.

A still further form of screen structure is illustrated in Figure 11 and which comprises an inner layer 128 of number 14 gauge hit and miss diagonal screen, an adjacent layer 129 of Monel metal screen cloth, a further layer 131 of number 6 mesh rolled brass screen and an outer comparatively thick layer 132 of number 6 gauge steel screen. The three layers 128, 129 and 131 have their edges turned outwardly and secured in position by the knife bars 99.

With the press cage 82 having the screen sections and knife bars mounted therein as above disclosed secured between castings 15 and 18 in enclosing relation to the screw flight sections 57 to 63 and spacing members 64 to 68 carried by shaft 36, a press barrel of cylindrical formation is provided for the passage of material therethrough under compression by the screw flights which flights aid in the movement of the material thru said barrel.

Casting 15 is provided with an integral hopper member 133 above screw flight section 57 for the feeding of material into the press barrel and a hopper bottom is provided beneath screw flight section 57 which bottom preferably comprises a pair of arcuate solid cast iron members 134 swingingly mounted on casting 15 beneath hopper member 133 thus providing a hopper bottom readily releasable for cleaning purposes.

Casting 18 is provided with a bore 136 of substantially greater diameter than screw flight section 63 and detachably secured within bore 136 by securing elements 137 is a ring member 138 the inner surface of which is in substantial spaced relation to the outer surface of screw flight section 63 thus providing a substantially wide circular material discharge opening 141.

In accordance with the invention means are provided for adjusting the width of discharge opening 141 for thereby regulating the thickness of cake as well as the pressure within the press barrel, such means comprising the aforementioned cone member 37 which is provided with an enlarged cylindrical section 142 for telescopic engagement with the adjacent end of screw flight section 63 and the cylindrical section 142 is tapered adjacent the free edge thereof thus defining a conical surface 143 whereby upon movement of cone member 37 toward or away from section 63 and within ring member 138 the opening 141 is correspondingly reduced or enlarged to its maximum opening by movement of the conical end of extension 142 within discharge opening 141. Means are provided for moving cone member 37 longitudinally of shaft 36 which in a preferred embodiment thereof comprises a hand wheel 145 having an integral hub portion 146 threaded engaged with the outer threaded end 147 of shaft 36. The cylindrical cone member 37 adjacent the outer end thereof is provided with a circular recess 148 for the reception of the inner edge of a sectional disc member 149 remov- 75

ably secured to hub member 146 by bolts 151. Thus with this construction upon turning hand wheel 145 in one direction or the other the hub portion 146 will, due to its screw connection with shaft 36, revolve about the shaft and move longitudinally thereof and as disc member 149 is rotatable in recess 148 longitudinal movement will be imparted to cone member 37 commensurate with the longitudinal movement of hub member 146.

The pan member 12 heretofore referred to extends the full length of the expressing screw composed of the multiplicity of sections 57 to 63 inclusive and is of a width substantially greater than the diameter of the press cage 82 as is clearly illustrated in Figure 2 and is adapted to collect the oil expressed from the material within the press barrel. The pan member 12 which is illustrated in transverse section in Figure 3 comprises opposite side members 151 integrally connected by a plate 152 which as clearly indicated in Figure 3 is slightly inclined to the horizontal and which plate together with portions of sides 151 and suitable end members define an oil receiving receptacle 153. The side members 151 project substantially below plate 152 defining with plate 152 and a detachable cover plate 154, a water jacket 155, the cover plate 154 being removably secured in position by stud bolts 156 threaded into bosses 157 integral with plate 152. The oil receptacle 153 adjacent the lower side of bottom plate 152 is provided with a screen 158 and the oil after passing thru said screen is withdrawn from receptacle 153 thru a pipe connection 161. The water jacket 155 is adapted for the circulation of hot water for maintaining the oil substantially fluid whereby the same may be easily pumped from receptacle 153, the hot water entering jacket 155 by way of a pipe connection 162 and discharging from said water jacket by way of an outlet pipe connection 163.

The novel press structure in accordance with the present invention embodies a novel drive arrangement for imparting rotation to shaft 36. The driving arrangement in a preferred embodiment thereof comprises a gear 165 suitably keyed to shaft 36 immediately within cover plate 32 as indicated at 166 in Figure 2. The gear 165 is in meshing engagement with a pinion 167 keyed at 168 to a stub shaft 169 the opposite ends of which are mounted within roller bearing assemblies 171 and 172 carried by bearing cages 173 and 174 removably secured in apertures in housing 22 and cover plate 32 respectively by means of stud bolts 175 as clearly indicated in Fig. 2. Stub shaft 169 embodies a central enlarged section 176 against one face of which pinion 167 bears and a collar 177 is disposed between the opposite face of pinion 167 and the proximate bearing assembly 172. Keyed to stub shaft 169 in engagement with the opposite face of enlargement 176 and maintained in spaced relation to the adjacent bearing assembly 171 by a collar 179 is a gear 181. Gear 181 is in meshing engagement with a pinion 182 keyed to a stub shaft 183 whose opposite ends are rotatably mounted in roller bearing assemblies 184 and 184' supported in bearing cages 185 and 186 removably mounted within apertures in housing 22 and cover plate 32 respectively by means of stud bolts 187. Stub shaft 183 projects substantially outwardly of housing 22 as indicated at 188 and mounted on the extension 188 of shaft 183 is a drive sprocket 189, one end of the hub portion 191 of which engages a collar 192 removably

secured to shaft 183 by means of a set bolt 193 and engaged with the opposite end of hub member 191 is a collar 194 removably keyed to shaft 183 as indicated at 195 and connected to sprocket 189 by means of a shear pin 195' whereby upon jamming in the press, pin 195' will shear and thus break the driving connection.

It will be seen upon reference to Figures 2 and 4 that housing 32 is of substantial transverse elongation with shaft 183 spaced a substantial distance laterally of shaft 36 and that the top portion of housing 22 is substantially horizontal thus providing a convenient support for power mechanism about to be described. Suitably secured to or integral with housing 22 is a pair of lugs 197 which are spaced a substantial distance parallel with shaft 36. Pivoted secured to lugs 197 by means of a pintle rod 198 are ears 199 projecting inwardly from one side of a motor support 201, the ears 199 engaging lugs 200. Support 201 adjacent the opposite side thereof is provided with a pair of longitudinally spaced ears 202 through which extend a rod 203 which rod 203 adjacent ears 202 projects through the eyes of eye bolts 204, which eye bolts project through lugs 205 formed on housing 22 and each bolt 204 has engaged therewith a nut 206 for engagement with each vertically opposite face of the respective lug 205 whereby upon turning nuts 206 in one direction or the other support 201 may be raised or lowered about pintle rod 198 for a purpose later referred to.

Suitably mounted on support 202 is an electric motor 208 to the drive shaft 209 of which is suitably secured a sprocket 211 which sprocket 35 is in driving engagement with the drive sprocket 189 by means of a sprocket chain 212. For effective driving of sprocket 189 from sprocket 211 it is important that chain 212 be maintained sufficiently taut which is readily accomplished by 40 adjusting motor support 201 upon turning nuts 206 in one direction or the other.

Secured to shaft 183 intermediate bearing assembly 184 and drive sprocket 189 is a relatively small sprocket 213 about which is trained a 45 sprocket chain 214 operatively engaged with a sprocket 215 on the shaft of pump 159 whereby pump 159 is operated upon rotation of shaft 183.

The present invention includes in addition to the press construction above disclosed a tempering apparatus in which the material is heated, agitated and placed in suitable condition for most effective extraction of the oils therefrom by the press and from which tempering apparatus the material is fed into the press structure. 55

The tempering apparatus comprises a casing member 221 which as more clearly illustrated in Figure 4 comprises parallel sides 222 merging into a semi-cylindrical bottom portion 223. The outer edges of side members 222 are reinforced by angle bars 224. Integral with the semi-cylindrical bottom portion 223 is a similarly shaped wall 225 in slightly spaced relation to bottom portion 223 for providing a steam jacket 226 which as illustrated in Figure 4 extends substantially one-half the depth of casing 221. The jacket 226 is adapted for the condensation of live steam which is admitted thereto thru connections 227 and a suitable drain connection 228 is provided in the bottom of the jacket. The material to be treated is fed into the casing 221 to be subjected to heat from said steam jacket as well as to a beating action by mechanism about to be described. A rotatable shaft 231 is disposed within casing 221 preferably concentric 75

- with bottom 226 and is journaled in bushings 232 (only one of which is illustrated) in bosses 233 formed on end plates 234 and 235. Secured to shaft 231 are a plurality of longitudinally spaced beater arms 236 which as illustrated in Figure 1 are of sectional formation to facilitate attachments to shaft 231 and the arms 236 are preferably arranged at an angle of 90 degrees to each other in the successive longitudinal series thereof. Secured to the outer end of each of the arms 236 is a beater 237, the outer edge of which is in close proximity to the inner surface of bottom 223.
- Secured to the outer end of press shaft 36 is a sprocket 239 in vertical alignment with a similar sprocket 241 secured to the outer end of shaft 231 and rotation of shaft 36 is imparted to shaft 231 by a sprocket chain 242 operatively engaged with sprockets 239 and 241. As indicated in Figure 1 shaft 231 projects substantially outwardly of end plate 235 in order to secure sprocket 241 in vertical alignment with sprocket 239 and the extended portion of shaft 231 adjacent sprocket 241 is journaled in a bearing member 244 supported from end plate 32 of the press by a suitable bracket 245.
- Upon rotation of shaft 36 for operation of the press structure, shaft 231 is simultaneously rotated by sprockets 239 and 241 and chain 242 and in operation of the combined structure the material is fed into casing 221 and is subjected to a beating action within the casing 221 by the beaters 237 as well as by heat from the steam jacket 226.
- Casing member 221 is provided with a vertically disposed depending cylindrical section 247 in vertical alignment with press hopper 133 for the passage of the material after treatment in the tempering apparatus directly into the feed end of the press barrel, the section 247 having suitably secured thereto an angle ring member 248, the horizontal portion of which rests upon a horizontal flange 249 of hopper 133 and is secured thereto by bolts 251. The present invention comprises means for feeding the material from the discharge end of casing 221 into and thru the press hopper 133. Such means in a preferred embodiment thereof comprises a screw 252 of relatively great pitch disposed vertically and centrally within hopper 133 and section 247 upon the rotation of which the material is urged vertically downward from the discharge end of casing 221 into the feed end of the press structure. Screw 252 embodies a cylindrical body portion 253 thru which extends a vertically disposed shaft 254 to which body portion 253 is suitably secured for rotation therewith. Shaft 254 projects slightly beyond the lower end of body portion 253 and is rotatably journaled in a bearing bar 256 extending transversely of hopper 133 with the ends thereof suitably secured in the wall of said hopper, the bar 256 serving as a support and bearing mount for the screw. Shaft 254 projects vertically outwardly of body portion 253 and is rotatably journaled at spaced points adjacent the outer end thereof in bushings 257 disposed in a bearing boss 258 projecting inwardly of and integral with a plate 259 extending over casing 221 adjacent one end thereof and suitably secured in position by bolts 261, the casing 221 being open from end to end except for the portion covered by plate 259. Secured to the outer end of shaft 254 is a bevel gear 262 in meshing engagement with a similar bevel gear 264 secured to a longitudinally disposed shaft 265 rotatably journaled in bearings 266 supported on brackets 267 projecting outwardly from plate 259. Shaft 265 extends substantially beyond one of the bearings 266 and has secured adjacent the end thereof a sprocket 269 about which is trained a sprocket chain 271 in operative engagement with a somewhat larger sprocket 272 secured to shaft 231 in vertical alignment with sprocket 269 whereby upon rotation of shaft 231 occasioned by rotation of shaft 36 shaft 265 is rotated which in turn imparts rotation to shaft 254 and consequently screw 252 for urging the material from the discharge end of the tempering apparatus into the feed end of the press structure.
- In operation of the construction disclosed motor 208 is set into operation which imparts rotation to the press shaft 36 thru the cooperating sprocket 211, chain 212, sprocket 189, pinion 182, gear 181, pinion 167 and gear 165 and due to the substantially large sprocket 189 and gears 181 and 165 in comparison to sprocket 211 and pinions 182 and 167 the shaft 36 will be rotated at a substantially reduced speed relative to the motor shaft 209 as it is desirable for most effective operation that the screw actuated by shaft 36 be rotated relatively slow within the press barrel formed by screen 98. Upon rotation of shaft 36 the tempering apparatus shaft 231 is rotated at a speed slightly greater than that of shaft 36 and rotation of screw 252 is imparted from shaft 231 thru sprockets 272 and 269 and chain 271 and the meshing gears 262 and 264 and as sprocket 269 is substantially smaller than sprocket 272 screw 252 will be rotated at a speed substantially greater than the rotation of shaft 231. With the cooperating parts set into operation as above described the material is fed into casing 221 of the tempering apparatus where the material is subjected to a beating action by the revolving beaters 237 which together with the heat to which the material is subjected from the steam jacket 226 places the material in a condition for most effective pressing operations and the material adjacent the discharge end of the tempering apparatus is constantly fed into the feed end of the press structure by screw 252 whereby the material enters the press structure by hopper 133 and falls upon the first screw flight section 57 which section together with the succeeding sections 58 and 63 is rotated with shaft 36 and the material will be fed longitudinally of the press barrel formed by screen 98 by the screws on the screw flight sections and it is to be noted that the screw flight sections comprise cylindrical hubs of successively increasing diameter from section 57 to 63 and that the screw flights on sections 58 to 63 are of equal pitch while the screw flight on section 57 is of greater pitch whereby as the material is progressed forwardly by the screw flights it is subjected to constantly increased pressure toward the discharge end of the press and by the provision of the checks 103 on knife bars 99 the material is substantially retarded in its circular motion with the screws thus further aiding in sufficient pressure thereto to extract a maximum amount of oil therefrom. The compression within the press barrel is further controlled by adjustment of cone 37 whereby the thickness of cake expelled from the discharge opening 141 may be varied with corresponding variation of pressure within the press barrel. The material is forced by the screw flights into pressure engagement with the screen 98 which screen and particularly the form illustrated in Figures 5 and 6 holds the body of material but permits the passage of the oil 75

through the slits 116 therein. As the oil is pressed outwardly through the slits 116 or relatively small openings in any of the other forms of screen disclosed it falls downwardly over the press cage 82 and by spacing ribs 93 from the outer surface of the screen member as indicated at 94 the oil is permitted to flow downwardly between ribs 91 on the outer surface of screen member 98 into the pan 12 from which the oil is constantly pumped by pump 159 driven from shaft 183 in the manner heretofore disclosed.

From the foregoing disclosure it will be seen that a combined tempering apparatus and press construction is provided which is of comparatively simple construction and well adapted to perform the functions of constructions of this character and that the operating parts thereof are driven by relatively simple drive mechanism substantially completely housed and that the drive mechanism is operated by a motor adjustably mounted on the drive mechanism housing.

By constructing the press cage 82 in sections with the mating faces thereof in a vertical plane as disclosed, the cleaning thereof is greatly facilitated since upon refracting the upper bolts 85 as well as bolts 86 the sections 83 after removing bolts 95 can be individually lowered about the lower bolts 85 thus exposing each section interiorly thereof in a vertical position for easy and thorough flushing thereof. This arrangement of the cage sections 83 further provides for ready access to the interior of the cage for inspection or replacement of parts.

Another feature of novelty to which attention is directed is the simple adjustment of the exit opening for the cake, whereby the pressure within the press may be adjusted. It will be noted that hand wheel 145 extends outwardly from the end of the press clear of all parts and spaced below the tempering casing 221. By a simple rotation of this hand wheel, the cone 31 with the sloping end 143 thereof may be moved closer or further away from exit opening 138.

It will also be noted that the driving motor with the gear on the shaft thereof is mounted above and to one side of the machine on a unitary support 201, the support being simply and easily adjustable by screw bolts 204 and nuts 206 to adjust the tension on drive chain 212.

Although the invention has been illustrated in detail to show a complete and operative machine, it will be understood that I am not limited to the details thereof except as stated in the accompanying claims, since various additions, omissions and modifications may be made without departing from the spirit and scope of the invention.

What I claim as new and desire to secure by United States Letters Patent is:—

1. In an expressing press, a screen structure comprising a body for surrounding an expressing means, said body being formed of two mating sections, each section having two vertical flanges and a series of ribs united thereto, the ribs of each section forming a hollow semi-cylindrical shell; a plurality of trapezoidal bars rigidly unite together at longitudinally spaced points to form a semi-cylinder for positioning within said shell, said bars having outwardly diverging slots; and means to detachably secure said set of bars to said semi-cylindrical shell.

2. The invention as defined in claim 1 wherein the vertical flanges of said body are rabbeted at the inner edges to form rabbets, and the means

to detachably secure the bars to the shell comprises knife bars secured in said rabbets.

3. In an expressing press of the type having a rotary pressing screw, a frame surrounding the screw comprising two identical semi-cylindrical mating sections extending in an axial direction along the length of the screw, each section having longitudinal diametrically opposite outwardly extending flanges for mating engagement with similar flanges on the other section; ribs on each section secured at longitudinally spaced points to said flanges, said ribs defining a semi-cylindrical shell; a plurality of bars rigidly secured together at longitudinally spaced points to form a semi-cylinder for positioning within said shell, slots being defined therebetween; said flanges of said mating sections being rabbeted at their inner edges; and inwardly projecting notched knife bars removably secured within the rabbeted portions of said sections. 20

4. In an expressing press of the type having a rotary pressing screw; a frame surrounding the screw comprising two identical semi-cylindrical mating sections extending in an axial direction along the length of the screw, each section having longitudinal diametrically opposed outwardly extending flanges for mating engagement with similar flanges on the other section, ribs on each section secured at longitudinally spaced points to said flanges, said ribs defining a semi-cylindrical shell; a plurality of bars lying end to end and side by side forming a semi-cylinder in each section and contacting said ribs, slots being defined between sides of adjacent bars; said flanges of said mating sections being rabbeted at their inner edges; and inwardly projecting notched knife bars removably secured within the rabbeted portions of said sections. 30

5. In an expressing press of the type having a

rotary pressing screw; a frame surrounding the screw comprising two identical semi-cylindrical mating sections extending in an axial direction along the length of the screw, each section having longitudinal diametrically opposed outwardly extending flanges for mating engagement with similar flanges on the other section, ribs on each section secured at longitudinally spaced points to said flanges, said ribs defining a semi-cylindrical shell; a plurality of bars lying side by side forming a semi-cylinder in each section and contacting said ribs, slots being defined between sides of adjacent bars; said flanges of said mating sections being rabbeted at their inner edges; and inwardly projecting notched knife bars removably secured by screws within the rabbeted portions of said sections, said knife bars cooperating to hold said first mentioned bars in position. 55

6. In a press of the class having a tubular screen structure and rotary screw means within said structure; a tubular press cage therefor comprising a plurality of mating sections, each section including spaced arcuate ribs secured to outwardly extending flanges, adjacent flanges of adjacent sections being held together by fastening members passing through said flanges, the inner edge of said adjacent flanges being recessed; a knife bar seated in said recess and extending in an axial direction along the length of said screw means; and spaced fastening members passing through said knife bar for holding the knife bar flush against a flange. 60

7. In a press of the class having a tubular screen structure and rotary screw means within said structure; a tubular press cage therefor comprising a plurality of mating sections, each sec- 75

tion including spaced arcuate ribs secured to outwardly extending flanges, each of said flanges being integrally formed and extending in an axial direction along the length of said screw means, adjacent flanges of adjacent sections being held together by fastening members passing through said flanges whereby material is precluded from passing out of said cage along the plane of contact of said flanges, the inner edge of said adjacent flanges being recessed; and a knife bar seated in said recess and extending in an axial direction along the length of said screw means, each side of said knife bar being held flush throughout substantially its entire length against a plane surface to preclude passage of material past said sides and to provide a rigid structure capable of withstanding stresses caused by impact of material against said knife bar.

8. In a press of the class having a tubular screen structure and rotary screw means within said structure; a tubular press cage therefor comprising a plurality of mating sections, each section including spaced arcuate ribs secured to outwardly extending flanges, each of said flanges being integrally formed and extending in an axial direction along the length of said screw means, adjacent flanges of adjacent sections being held together by fastening members passing through said flanges whereby material is precluded from passing out of said cage along the plane of contact of said flanges, the inner edge of said adjacent flanges being recessed; a knife bar seated in said recess and extending in an axial direction along the length of said screw means; and means including fastening members passing through said knife bar and secured to a flange for holding said knife bar in position; each side of said knife bar being held flush throughout substantially its entire length against a plane surface to preclude passage of material past said sides and to provide a rigid structure capable of withstanding stresses caused by impact of material against said knife bar.

9. In a press of the class having a tubular screen structure and rotary screw means within said structure; a tubular press cage therefor comprising a plurality of mating sections, each section being a unitary structure including a plurality of arcuate spaced apart ribs secured to outwardly extending flanges, each of said flanges being integrally formed and extending in an axial

direction along the length of said screw means, adjacent flanges of adjacent sections being held together, the inner edge of a flange being formed with a recess extending substantially the length of said flange and open on the inner side of said flange, said recess being of such shape as to snugly receive the outer part of a knife bar therein; and a knife bar seated snugly in said recess and extending substantially the length of said flange.

10. In a press of the class having a tubular screen structure and rotary screw means within said structure; a tubular press cage therefor comprising a plurality of mating sections, each section being a unitary structure including a plurality of arcuate spaced apart ribs secured to outwardly extending flanges, each of said flanges being integrally formed and extending in an axial direction along the length of said screw means, adjacent flanges of adjacent sections being held together, the inner edge of a flange being formed with a recess extending substantially the length of said flange and open on the inner side of said flange, said recess being of such shape as to snugly receive the outer part of a knife bar therein; a knife bar seated snugly in said recess and extending substantially the length of said flange; and fastening members passing through said knife bar and secured to said flange for holding the knife bar in position.

11. A press cage section including a rigid integrally formed structure of spaced members terminating in flanges spanning the spaces between the members, the inner edge of a flange being provided with a knife bar recess extending substantially the length of said flange, said recess being open on the inner side of said flange; and a knife bar seated in said recess.

12. A press cage section including a rigid integrally formed structure of spaced members terminating in flanges spanning the spaces between the members, the inner edge of a flange being provided with a knife bar recess extending substantially the length of said flange, said recess being open on the inner side of said flange; a knife bar fitting snugly in said recess; and fastening members passing through the knife bar securing the knife bar to said flange with a side of said knife bar abutting said flange.

STANLEY HILLER. 50
